JAMES BEYANT WHITMORE AND JOHN MELING FERGUSON, OF BLOOMFIELD, NEW JERSEY, ASSIGNEES TO WESTINGHOUSE LAMP COMPANY, A CORPORATION OF PENNSYLVANIA.

POTENTIAL DETECTOR.

Application filed January 30, 1923. Serial No. 539,535.

This invention relates to potential detectors of the gas-filled tube type and particularly to potential detectors of the character employer for testing current and ignition conditions in internal combustion engines.

An object of the present invention is to provide a device of the above mentioned character having its component parts so constructed as to facilitate the manufacture of the device.

Another object of this invention is to provide a device with an element which will serve as a conductor and which may also operate to secure the gas-filled tube from lateral and longitudinal movements.

Further objects will be apparent from a reading of the following description.

Potential detectors of the type to which my invention is applicable usually comprise an outer casing of a non-conducting substance, and of sufficient density and thickness as to resist the passage of an electrostatic charge when the device is in use. The casing serves as the dielectric in a condenser, the inner armature of the condenser being composed of copperfoil of cylindrical form and inserted into the casing at one end. At the other end of the casing is mounted a gas-filled tube having an electrode projecting therefrom and in contact with the copperfoil.

The tube may be provided with a constricted portion which, when the tube is in position within the casing, is disposed opposite a window in the casing, the constriction serving to concentrate and intensify the brilliancy of the discharge increasing its visibility through the window.

The present invention contemplates an improvement in the structure of potential detector devices as above briefly described and particularly a device of the type described and claimed in a copending application Serial No. 504,000, filed September 28, 1921, and assigned to the same assignee as is the present invention.

A device of this character has vast utility as a detector in connection with high tension lines and especially for detecting faults in the ignition systems of automobile engines. It will be appreciated that the demand for an article of this kind is such as to bring it in the class of volume production and obviously when it becomes necessary to

produce an article in large quantities, an expeditious and economical assembly of the component parts of the device is essential. Furthermore, such parts, when assembled, must provide a sturdy construction, the component parts of which must perform their respective functions equally as well as in a device upon which a comparatively large amount of time has been expended.

Heretofore, the assembly of the several parts which constitute a potential detector involved considerable loss of time, especially in handling and positioning the conductor composed of a sheet of copperfoil and forming a part of the condenser. The copperfoil was usually rolled into cylindrical form and inserted into the casing in such manner that a leading-in wire connected with electrodes within the tube would make contact with the foil. This construction, although efficient in so far as practical operation of the device is concerned, made it necessary for the operator to perform several time-consuming operations; it being necessary to handle a cylinder or mandrel to shape the foil into the desired form. This latter operation especially, tended to retard the desired increase in production.

The present improvement consists in providing the operator with foil in the form of corrugated sheets which may quickly be rolled into tubular form without the employment of a mandrel. The operator then thrusts a tube of foil into the casing so as to secure one or more of the leading-in wires of a previously positioned gas-filled tube, between the casing and the foil. The leading-in wires or conductors are thereby disposed in respective grooves or undulations of the foil and in contact therewith. The leading-in wires being firmly secured between the conductor, or tube of foil and the casing, they also serve as a resilient support and maintain the discharge or glow tube from lateral and longitudinal movements.

The invention will be more fully understood by reference to the accompanying drawing in which,

Fig. 1 shows a sheet of foil prior to its being shaped into a tubular conductor for insertion into a casing;

Fig. 2 shows the foil when bent to tubular form and in position for entrance into a casing of a potential detector, part of the latter being broken away;

Fig. 3 shows a potential detector partly in section and with the foil in its final position; and

Fig. 4 is a transverse section taken on line IV—IV in Fig. 3.

The potential detector illustrated in the drawings and to which my invention is applied, comprises an outer casing 6 having an aperture or window 7 and a tapered end 8. 10 A gas-filled tube 9 is suitably positioned within the casing and in the present construction one end is supported by a resilient washer 11 and the other end by the engagement of leading-in wire or wires 12 between a conductor 14 and the wall of the casing 6. The leading-in wires are connected with an electrode within the tube. The conductor 14 is originally supplied to an operator in the form of a sheet of corrugated copper or 20 other metallic foil 15 which may be quickly and conveniently shaped to cylindrical or generally tubular form for insertion into the casing.

This corrugated or crimped conductor is 25 not only easily adjusted for insertion into the casing but also possesses a considerable degree of resiliency; that is, after being coiled to tubular shape it has a tendency to 30 assume its original shape or uncoil with the result that when inserted in the casing it provides a comparatively firm contact with the wall thereof.

When assembling the several parts of the device, the gas-filled tube is previously 35 provided with a washer 11 and inserted into the casing to approximately the position shown in Fig. 2. The tubular conductor 14 is then disposed as indicated and thrust inwardly causing the free ends of the leading- 40 wires 12 to assume positions parallel with the walls of the casing and between the latter and the tubular conductor or foil 14. Further movement of the conductor into the casing carries with it the gas-filled tube 9 45 thereby positioning the tube in proper relation to the window 7. It will be evident that the leading-in wires 12 may be conveniently guided into grooves in the conductor 14 and as the conductor 14 is 50 moved the wires are guided into positions between the conductor and the wall of the casing 6, and the resilient property of the conductor secures the leading-in wires thereby 55 securing the discharge tube 9 in a given position with respect to the walls of the casing.

When the conductor is thus disposed with- 60 in the above described relation to the other parts of the device, it will be evident that the leading-in wires are secured and thus aid in preventing longitudinal movement of the tube 9 as well as preventing lateral move- 65 ment of one end of the tube.

Furthermore, the necessity of a washer, 65 similar to the washer 11, is avoided making

the device more economical as to material and reducing the cost of assembly.

After the conductor 14 has been disposed in its final position, a resilient washer 16, preferably of felt, is positioned thereon and 70 the casing is closed by the insertion of a plug 17 which may be cemented or otherwise secured thereto. The washer 16 may be made to fit the inside of the casing, the crimped conductor 14 providing sufficient 75 bearing surface for the washer to prevent it from being displaced. It will be understood that the inward movement of the tube 9 causes its opposite or second electrode 18 to pass through an aperture in a metallic 80 tip 19 to which the second electrode is preferably soldered, thus providing a metallic contact member.

The tube 9 may be provided with one leading-in wire 12 but for practical reasons 85 in the manufacture of the discharge tube it is preferable to provide two such leading-in wires constituting extensions from an electrode 13 within the tube 9. These double 90 leading-in wires are utilized to give a more substantial support to the tube and a more positive connection between the conductor 14 and the electrode 13.

While we have herein shown and particu- 95 larly described a preferred embodiment of the invention, it is to be understood that the invention is not limited to the precise details of construction illustrated, as modifications may readily be made without departing from the spirit and scope of the ap- 100 pended claims.

What is claimed is:

1. A potential detector comprising a cas- 105 ing, a discharge tube and a corrugated con- ductor disposed therein and leading-in wires projecting from said tube and positioned be- 110 tween said conductor and a wall of said cas- ing to prevent lateral movement of said tube.

2. A potential detector device comprising 110 a casing, a discharge tube and a corrugated tubular conductor positioned therein and leading-in wires projecting from said tube and disposed between said conductor and a wall of a casing to prevent lateral move- 115 ment of said tube.

3. A potential detector device comprising 120 a casing, a discharge tube and a conductor in the form of a coil disposed within said casing and leading-in wires projecting from said discharge tube and disposed between the outer side of said conductor and the inner wall of said casing, whereby the expansive 125 action of said coil secures said leading-in wires and prevents lateral movement of said tube.

4. A potential detector device comprising 130 a casing, a discharge tube and a corrugated conductor in the form of a coil disposed within said casing and leading-in wires pro-

jecting from said discharge tube and positioned between said conductor and the casing, whereby the expansive action of said coil secures said wires and prevents lateral 5 movement of said tube.

5. A potential detector device comprising a casing, a discharge tube mounted within said casing, a conductor comprising a sheet of resilient material shaped in the form of 10 a coil and leading-in wires projecting from said discharge tube and disposed between said conductor and said casing to prevent lateral movement of said discharge tube.

6. A potential detector device comprising 15 a casing, a discharge tube mounted within

said casing, leading-in wires projecting from said tube, a conductor comprising a sheet of resilient material having grooves disposed transversely thereof, said sheet being shaped in the form of a coil for the purpose of securing said leading-in wires between the outer surface of said coil and the wall of the casing to provide an electrical contact therewith and to prevent lateral movement of said discharge tube. 20

In testimony whereof, we have hereunto subscribed our names this 27 day of January 1922:

JAMES BRYANT WHITMORE.
JOHN EBLING FERGUSON. 25
